UNITED STATES PATENT OFFICE.

LOUIS FRITZ, OF PHILADELPHIA, PENNSYLVANIA.

LOW-WATER SIGNAL FOR STEAM-BOILERS.

SPECIFICATION forming part of Letters Patent No. 536,988, dated April 2, 1895.

Application filed October 2, 1894. Serial No. 524,729. (No model.)

To all whom it may concern:

Be it known that I, LOUIS FRITZ, a citizen of the United States, residing at Philadelphia, in the county of Philadelphia and State of 5 Pennsylvania, have invented a new and Improved Low-Water Signal for Steam-Boilers, of which the following is a specification.

The object of my invention is to provide a low-water signal of simple construction and 10 effective in operation, by which sounds are given when the water in the boiler has reached the "low-water mark;" and a further object is to so construct, adapt and assemble the different parts constituting the signal as to be 15 applicable to any boiler or its fixture, as steam gages or water-columns.

To apply my improved signal to water-columns or boilers, it is only necessary to unscrew the lower two of the try or test cocks 20 and attach the signal by means of pipe nipples and pipe T's without it being necessary to drill and tap holes for such connection, or for the mounting of the two unscrewed test cocks, which are fitted onto one branch of the 25 pipe T's, as will be more fully explained.

The improved low-water signal consists of parts constructed and assembled as hereinafter more fully described and pointed out in the claims.

30 My invention will be more fully understood taken in connection with the accompanying drawings forming part hereof, in which—

Figure 1 is a general view showing the application of the improved signal to a water-column. Fig. 2 is a plan view thereof. Fig. 3 is a vertical central section of my improved signal, showing the vessel communicating by two pipe connections with the boiler, the float therein having the valve stem, and a valve 35 seat and passages in the vessel cover to which the whistle or other sound-producing apparatus is attached. Fig. 4 is a similar section taken at right angles to the one shown in Fig. 3, and Fig. 5 is an under side view of the cover 40 or lid of the vessel showing the valve seat and port and passages leading thereto.

45 Referring now to the drawings for a further description of my invention, A is a vessel of cylindrical or other form having tapped connection holes a and a' and a cover a² removably applied to said vessel by bolts or any

other suitable means. In the center of this cover and extending into the vessel is formed integral therewith a stud or projection a³, which is bored to form a valve seat and port a⁴, 55 and the latter communicates with the interior of the vessel by means of the passages a⁵.

A' is a whistle or other steam-operated sound producing apparatus, attached in any suitable manner to the cover a², and having 60 its steam conduits in communication with the port a⁴.

B is a float of similar shape as the vessel A in which it is located and allowed to rise or fall according to the quantity of water contained in the boiler. This float is made of 65 suitable material and of sufficient strength to withstand the pressure of the steam. The top b and bottom b' thereof may be made flat, convex or concave, and the circular or other 70 side wall b² may or may not be provided with guide-beads or projections b³.

In the top b and bottom b' of the float are provided channels b⁴ and b⁵ respectively, which are in the same axial line and in the 75 axis of the connections fitted into the holes a and a' of the vessel A. These channels are of such dimensions in cross-section as that the free entering of water or steam on the top and bottom of the float is not obstructed for a 80 purpose to be more fully described.

A valve stem b⁶ is formed with or secured to the top b of the float B and is guided in a bore a⁶ of the stud a³ on the cover a², and the free extremity thereof is adapted to fit the 85 valve seat of the port a⁴, which may be of any shape desired. To prevent the float from turning, i. e., to retain the channels b⁴ and b⁵ in line with the connections in the holes a and a', the valve stem is provided with a pin 90 or projection b⁷ fitting into a slot a⁷ of the stud a³ in such a manner that the cover a² of the vessel A may be easily removed and the float allowed to rise and fall as will be understood.

95 In attaching my improved low-water signal, use is made of the two tap-holes provided for the lower two of three try or test cocks f, which are essential for the probing of the safety of the boiler. Into these tap-holes, 100 whether formed in the boiler shell D Fig. 3 directly, or in a water-column e attached by

two pipes e to the boiler D Figs. 1 and 2, are | screwed nipples i and pipe T 's i^2 . On one branch of the pipe T 's the two lower test cocks f are held, while in the remaining branch of 5 the respective T 's are screwed nipples i^3 having right and left hand threads, by which the vessel A by means of the connection holes a and a' is securely connected to the said T 's extending either from the boiler shell di- 10 rectly or from a water-column E connected with the boiler shell D as shown in Figs. 1 and 2.

The operation or working of the improved signal may be described as follows: The float 15 B is kept in an elevated position as shown in Fig. 3 as long as the water is above the axis of the connection a' or lower try cock f , and keeps the port a^4 to the whistle A' closed; but as soon as it falls below this axis, the steam 20 pressing on the top of the float B forces the same and the valve stem i^6 downward to admit steam contained in the vessel through the passages a^5 into the port a^4 and from here to the whistle or other signaling device, calling attention that the water has receded below the water mark.

A particular feature of my invention is to provide a float having greatest buoyancy combined with smallest floating area, so that the 30 signal is efficient in operation and neat in appearance and construction. For this purpose and for the purpose of reducing friction between float and vessel, which would result from the steam pressing directly on or against the wall of the float and bringing the latter into contact with the wall of the vessel A , the 35

channels b^4 and b^5 are provided in the top and bottom surfaces of the float.

The vessel A is provided with a blow-off cock g to remove suds and dirt or other matter collecting in the vessel. 40

Having thus described the nature and objects of my invention, what I claim as new, and desire to secure by Letters Patent, is—

1. In combination with a boiler, a low-water signal comprising a vessel, a float within the same, a valve stem on said float and a valve seat and port in the cover of the vessel, a signal attached to the cover of said vessel, a channel in the top and bottom surfaces of the 50 float coinciding in dimensions and relative positions with the connections between the boiler and the said vessel, substantially as and for the purposes set forth.

2. In combination with a boiler, a low-water 55 signal comprising a vessel having two pipe-connections, one above the other, with the boiler, a signaling device on top of the vessel, a float in said vessel provided with a channel at its top and bottom surface coinciding with 60 the said pipe-connections, a valve between the said float and vessel, and means for retaining the channels of the float in axial line with the said pipe-connections, substantially as and for the purposes set forth. 65

In witness whereof I have hereunto set my hand in the presence of two subscribing witnesses.

LOUIS FRITZ.
